UNITED STATES PATENT OFFICE.

FRANK F. JAQUES, OF CHICAGO, ILLINOIS.

DESIGN FOR A DISPENSING-FRONT FOR GROCERS' CABINETS.

SPECIFICATION forming part of Design No. 30,325, dated March 7, 1899.

Application filed February 8, 1899. Serial No. 704,979. Term of patent 3½ years.

To all whom it may concern:

Be it known that I, FRANK F. JAQUES, a citizen of the United States, and a resident of Chicago, in the county of Cook and State 5 of Illinois, have invented and produced a new and original Design for a Dispensing-Front for a Grocer's Cabinet, of which the following is a specification, reference being had to the accompanying drawings, forming a part o thereof.

Figure 1 is a perspective view showing my new design for a dispensing-front for a grocer's cabinet. Fig. 2 is a top view thereof. Fig. 3 is a vertical central section on the line 15 3 3, Fig. 2.

As shown in the drawings, the leading or material feature of my design consists in the

dispensing-front, comprising the segmental body having a bottom plate formed with a horizontal outer portion and an upwardly-inclined inner portion, a downwardly-tapering projection at the back, and a wall surmounting the top of the body in front of the projection. 20

Having thus described my invention, the 25 following is what I claim as new therein and desire to secure by Letters Patent:

The design for a dispensing-front for a grocer's cabinet, substantially as herein shown and described.

FRANK F. JAQUES.
